UNITED STATES PATENT OFFICE

LEE E. BEREBAUM, OF CHICAGO, ILLINOIS.

FABRIC-CLASP.

1,154,362.

Specification of Letters Patent. Patented Sept. 21, 1915.

Application filed May 16, 1913. Serial No. 768,009.

To all whom it may concern:

Be it known that I, LEE E. BEREBAUM, a citizen of the United States, residing at Chicago, in the county of Cook and State of Illinois, have invented certain new and useful Improvements in Fabric-Clasps, of which the following is a specification.

My invention relates to improvements in clasps and has a special reference to garment or fabric clasps.

One of the objects of my invention is to provide a clasp that is adapted to be easily and quickly adjusted, attached or disengaged, without requiring the use of both hands; that engages relatively large surfaces of the fabric, so as not to concentrate its grip on a few strands; that is not provided with cutting edges; that is cheap of construction, durable and convenient in operation.

Other and further objects of my invention will become readily apparent to persons skilled in the art from a consideration of the following description when taken in conjunction with the drawing, wherein;

Figure 1 is a front elevation of one form of my clasp showing it in operative position and a fragment of fabric with which it is shown to be engaged. Fig. 2 is a section on line 2—2 of Fig. 1, showing the jaws closed. Fig. 3 is a side elevation of the device showing the jaws disengaged or open. Fig. 4 is an elevation of the back jaw member in a slightly modified form. Fig. 5 is an isometric view of the disengaging member shown in Figs. 1, 2 and 3. Fig. 6 shows a modified form of the disengaging device. Fig. 7 is a central section of the front member and disengaging member taken on line 7—7 of Fig. 6. Fig. 8 shows another slight variation in the shape of the clasping jaws. Fig. 9 is a section taken on line 9—9 of Fig. 8. Figs. 10 and 11 show two views front and side elevation, respectively, of a modified form showing means for covering the rear metal surface of the back clasping member with fabric, celluloid, or the like. Fig. 12 is a sectional view of means for covering the rear surface of the rear clasping member with a supporter or garter elastic webbing or fabric. Fig. 13 is a fragmentary front view of said rear clasping member.

In all the views the same reference characters are employed to indicate similar parts.

My improved clasp consists essentially of

the rear clasping member 15 and a front clasping member 16 hinged together as at 17. The jaw 18, of the rear clasping member, extends forwardly of the jaw 19 of the front clasping member, when the parts of the device are in closed position. The jaws are located on the free ends of the respective members, and consist of tubular formations produced by turning the ends of said members over upon themselves, as clearly shown in the drawings. The jaw 18, of the rear clasping member extends into the circumferential path of the jaw 19 of the front or forward clasping member, so that when the front clasping member is pressed into position it displaces the jaw 18 of the rear clasping member, and after the jaw of the front clasping member has been placed in the position shown, for instance in Fig. 2, the resilience of the portions 15 and 16 will cause the jaws to spring back together into place and retain the jaw 19 in closed position.

A disengaging device, 20, is carried by the front member 16. In the operation of disengaging the clamping members, the disengaging device 20 is moved from contact with the member 16 to the dotted line position shown in Fig. 3, whereby the shoulder 21, of said disengaging member, is brought forcibly into contact with the jaw 18 of the rear member, thereby displacing said jaw 18, out of the path of the jaw 19, and permitting the front member 16 to pass freely beyond the jaw 18, of the rear member.

To cause the front member 16 to move forwardly in an automatic manner I may cut or form a tongue 22 out of the portion 15, and cause this resilient tongue to bear forwardly upon the back surface of the member 16, as shown in Figs. 1, 2, and 3.

The free ends 20' of the disengaging member 20 in the preferred form finds bearing in the interior of the tubular jaw 19, and these free ends 20', of the disengaging device 20, are held together with more or less resilience by the spring loop 23 of said device and the terminals of the jaw 19 being inclined, as at 24, the tension thus produced on the portion 25 of the disengaging device, with reference to the inclines 24—24 of the front clasping jaw, causes the body portion of the disengaging device 20, to be returned to the position shown in full lines in Fig. 3, after it has been moved forwardly to the disengaging position shown in dotted lines and

thereby to be maintained in this position so as not to interfere with the subsequent use of the device. Other means for effecting this result may be employed within the contemplation of my invention, as for instance in Fig. 9 I have shown the disengaging device 20 to be an integral part of the front clasping member 16, instead of being hinged thereto, as shown in Fig. 3 and in the device shown in Fig. 9 the resilient elasticity of the material of which the disengaging device and the front member 16 are made, tends to yieldingly maintain the disengaging device 20 in the position shown in Fig. 9, and to return it to said position after it has been employed for the purpose intended. And other means than those specifically shown for effecting this result are within contemplation of the claims and may be employed with advantage. I have merely illustrated the modification shown in Fig. 9 to indicate that it is not essential that the parts 16 and 20 shall be separable parts, hinged together, as the modification shown in Fig. 9 will perform all of the functions in as satisfactory a manner, as are performed by the preferred form shown in Fig. 3.

In order to produce more tortuous path for the clasped fabric 25, between the clasping members, I preferably provide subsidiary jaws consisting of projection 26, in the rear clasping member, and projection 27, in the front clasping member, arranged so that the former will neatly nest in the latter, thereby to increase the frictional resistance of the fabric between the respective clasping members. In Figs. 1 to 3 inclusive these nesting members do not extend across the entire lateral extent of the clasping members, but in Figs. 4 and 6 I have shown them so extended operating substantially as corrugations and while the corrugations serve substantially the same purpose as the projections 26 and 27 they contribute somewhat to the resiliency of the respective clasping members to engage, hold and disengage or release the fabric.

When the device is to be used in connection with garters or hose supporters it is desirable to attach an elastic webbing 27 to the rear clasping member 15, or to the front clasping member 16. I prefer to attach the webbing 27 to the front clasping member so that the strain on the webbing will tend to normally hold the clamp closed, as shown in Figs. 1, 2 and 3, but it is within the contemplation of my invention to attach the webbing to either member and in Fig. 4 the rear clasping member is so formed that it may be attached to it. In Figs. 1 and 4 I have made provision for a relatively wide ribbon of elastic webbing 27 wherein a loop is formed by the members 28 and 29 leaving a space 30 therebetween so that the elastic

may be slipped into engagement with the member 15 or 16 without the necessity of slipping the elastic into the perforation 30, thus provided, before it is sewed, as at 31, and thereby the elastics may be easily and quickly applied to either of the clasping members.

In Fig. 8 I have shown the jaws 18 and 19 to be somewhat transversely curved instead of straight, as shown in the other figures, simply to indicate that such a modification is within the contemplation of my invention.

It is advantageous and desirable to cover the rear metal surface of the clasp, especially the rear member 15, with a material less offensive than the metal and to this end I show a means of accomplishing this result in Figs. 10 and 11 by cutting away a portion of the member 15, at its opposite edges, and thereby providing clips 32 that are bent back upon the body part of the member to clamp therebetween a thin sheet of celluloid, 33 or the like. The celluloid is then continued around the edge of the jaw 19 and fastened under the jaw terminal 19', as shown in Fig. 11. Another means of accomplishing this result is shown in Figs. 12 and 13 wherein members 34 and 34' integral with the clasp member 15 are bent back upon themselves to provide an opening in which to pass the end 29' of the elastic fabric or webbing 29 after which this fabric is passed around the clasping member 15 to prevent metal contact thereof with the flesh or body of the wearer. The tape 29 is now passed through the aperture 28 and continued to the part or object to which it is intended to be attached.

In the operation of the device it is only necessary to insert the fabric 25 between the jaws 15 and 16 and press the jaws together with the hand used in placing the clasp in operative position with the fabric. In this way the device may be quickly and easily applied without the necessity of using both hands, and it may be disengaged with the same attendant convenience, simply by applying the finger, or thumb, under the upper end 23 of the disengaging device 20, and pressing the same out into the position shown in dotted line in Fig. 3 whereby the jaw 18, of the member 15, is forced out of the path of the jaw 19 of the member 16 and the latter member is moved to open position by means of the resilient tongue 22, and thus the two jaws are always yieldingly held in open position ready for insertion of the fabric with which they are intended to engage.

The broad transverse area of the fabric engaged by the clasping device is so large as to prevent the possibility of concentrating the holding effect to a small area and thereby causing breaking of the thread or chains of the fabrics.

When the strain in a longitudinal plane applied to the members 25 and 29 becomes excessive, it will serve to open the clasp before damage to the fabric will occur and 5 thus a factor of safety is introduced into the operation of the device.

While I have shown several modifications for the purpose of indicating the direction to which changes in the illustrated exemplification may take I wish it understood that 10 I am not limited to the few and specific modifications shown but that my invention is intended to cover any and all modifications within the definition of the appended 15 claims.

What I claim is:

1. A device of the character described, comprising a rear member and a front member hinged together and each provided on 20 its free end with a clamping jaw, the jaw of the rear member located in front of the jaw of the front member when the latter is in closed position, and within the circumferential path of the jaw of the front member when the latter is moved from open to closed position, and a manually operable disengaging lever movably connected to the front member for separating said members.

2. A device of the character described, 30 comprising a rear member and a front member hinged together, and each provided on its free end with a clamping jaw, the jaw of the rear member located in front of the jaw of the front member when the latter is in closed position, and within the circumferential path of the jaw of the front member when the latter is moved from open to closed position, and a disengaging means 35 for separating said members yieldingly secured to the free end of the front member.

3. A device of the character described, comprising a rear member and a front member hinged together, and each provided on 45 its free end with a clamping jaw, the jaw of the rear member located in front of the jaw of the front member when the latter is in closed position, and within the circumferential path of the jaw of the front member when the latter is moved from open to 50 closed position, a disengaging means for separating said members, pivoted in the jaw of the front member, and means for yieldingly returning said disengaging member to normal, closed, position.

55 4. A device of the character described,

comprising a rear member and a front member hinged together and each provided on its free end with a clamping jaw, the jaw of the rear member located in front of the jaw of the front member when the latter is in closed position and within the circumferential path of the jaw of the front member when the latter is moved from open to closed position; an elastic tongue carried by one of said members adapted to separate 60 the members when the jaws have been disengaged and means carried by the device to disengage the members.

5. A device of the character described, 70 comprising a rear member and a front member hinged together and each provided on its free end with a clamping jaw, the jaw of the rear member located in front of the jaw of the front member, when the latter is in closed position, and within the circumferential path of the jaw of the front member, when the latter is moved from open to closed position; supplementary jaws, consisting of 75 a nesting elevation and depression carried, respectively, by said members and means, 80 carried by the front member for separating said members.

6. A device of the character described, 85 comprising a rear member and a front member hinged together and each provided on its free end with a clamping jaw, the jaw of the rear member located in front of the jaw of the front member when the latter is in closed position, and within the circumferential path of the jaw of the front member, 90 when the latter is moved from open to closed position, and a disengaging member hinged to the jaw of the front member and having a shoulder normally bearing on the jaw of the rear member for disengaging said members. 95

7. A device of the character described, 100 comprising a rear member and a front member hinged together, each member carrying a coöperating jaw; a disengaging member hinged to the jaw of the front member and having a shoulder normally bearing on the jaw of the rear member for disengaging said members.

In testimony whereof I hereunto set my hand in the presence of two witnesses.

LEE E. BEREBAUM.
